TWIN SOFA BED AND CORNER TABLE UNIT

Louis Elliott Frey, Los Angeles, Calif.

Application August 4, 1958, Serial No. 52,036

Term of patent 14 years

(Cl. D5—4)

Fig. 1.

Fig. 2.

Fig. 3.

Fig. 1 is a perspective view showing a twin sofa bed and corner table unit embodying my new design in closed position.

Fig. 2 is a perspective view of the same in open position.

Fig. 3 is an enlarged top plan view of the corner table. The dominant features of my design are shown in solid lines.

I claim:

The ornamental design for a twin sofa bed and corner table unit, substantially as shown and described.
